US0D1105072S

(12) **United States Design Patent** (10) Patent No.: **US D1,105,072 S**
(45) Date of Patent: ** Dec. 9, 2025

(54) **WIRELESS TRANSCEIVER**

(71) Applicant: **Shenzhen Yishengxing Technology Co., Ltd.**, Shenzhen (CN)

(72) Inventor: **Zhigang Cao**, Shenzhen (CN)

(73) Assignee: **Shenzhen Yishengxing Technology Co., Ltd.**, Shenzhen (CN)

(**) Term: **15 Years**

(21) Appl. No.: **29/953,664**

(22) Filed: **Jul. 23, 2024**

(30) **Foreign Application Priority Data**

Mar. 12, 2024 (CN) 202430124734.5

(51) **LOC (15) Cl.** **14-02**

(52) **U.S. Cl.**

USPC **D14/358**; D14/125

Primary Examiner — Marie D. Fast Horse

(57) **CLAIM**

The ornamental design for a wireless transceiver, as shown and described.

DESCRIPTION

FIG. 1 is a front perspective view of a wireless transceiver, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the wireless transceiver, which form no part of the claimed design.

1 Claim, 8 Drawing Sheets
